(57) **CLAIM**

The ornamental design for an aircraft headlight lens, as shown and described.

DESCRIPTION

FIG. 1 is a front, top perspective view of an aircraft headlight lens showing our new design and its environment;

FIG. 2 is a detail front, top perspective view thereof;

FIG. 3 is a front view thereof;

FIG. 4 is a side view thereof; and,

FIG. 5 is a top view thereof.

The portions of the drawings shown in broken lines indicate surrounding structure and environment that forms no part of the claimed design.
